Primary Examiner—Jeffrey Asch(74) *Attorney, Agent, or Firm*—Staas & Halsey LLP(57) **CLAIM**

The ornamental design for a cellular phone, as shown and described.

DESCRIPTION

FIG. 1 is a perspective view of a cellular phone according to my new design with its front closed;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the cellular phone according to my new design with its front opened; and,

FIG. 9 is a perspective view of the cellular phone according to my new design with its front opened and rotated.

The surface(s) or portion(s) of the article not shown in the drawing or described in the specification form(s) no part of the claimed design.
